BAG PRESSURE INDICATOR FOR SUCTION CLEANERS

Filed Oct. 2, 1935

UNITED STATES PATENT OFFICE

2,114,105

BAG PRESSURE INDICATOR FOR SUCTION
CLEANERSDale C. Gerber, North Canton, Ohio, assignor to
The Hoover Company, North Canton, Ohio, a
corporation of Ohio

Application October 2, 1935, Serial No. 43,141

3 Claims. (Cl. 116—65)

This invention relates to improvements in bag pressure indicators for suction cleaners, and more particularly to indicating devices responsive to the pressure within the dust receptacle or bag of a suction cleaner and serving to indicate visually either the condition of the bag or to warn the user that the same should be emptied of its contents.

The object of the invention is to provide a novel form of indicator adapted to be applied or attached to the bag, and preferably supported directly by the fabric thereof.

The novel features of the bag pressure indicator are clearly shown in the accompanying drawing, in which:

Figure 1 is a general view in side elevation of a suction cleaner showing the mounting of a pressure indicator adjacent the upper end of the dust bag.

Figure 2 is an enlarged detail view in cross section through the opening provided in the fabric to receive an indicator and showing a plug adapted to be inserted in the absence of such indicator.

Figure 3 is an enlarged plan view of one form of bag mounted pressure indicator as it appears to the operator.

Figure 4 is a cross-sectional view of the indicator, as taken on line 4—4 of Figure 3.

Figure 5 is a view in cross section taken on the line 5—5 of Figure 4.

Figure 6 is a top plan view of a modified form of bag mounted pressure indicator.

Figure 7 is a cross-sectional view of the bag pressure indicator shown in Figure 6 as taken on line 7—7 thereof, and

Figure 8 is a plan view of the bottom or inner side of the indicator shown in Figures 6 and 7.

Without going into detail, the suction cleaner herein disclosed comprises a wheeled casing 1 having a nozzle 2 opening downwardly in close proximity to the floor and communicating with a fan chamber in which is located a fan 3 driven by a motor enclosed within its casing 4. Leading from the fan chamber is an exhaust duct or passage terminating in an annular outlet connection 5 to which is attached one end of a fabric dust collecting bag 6, the same being supported at its upper end by a suitable flexible connector 7 to a handle 8 pivotally connected to the main casing 1 of the cleaner by means of a bail 9.

As well known in the art the cleaner is maneuvered over the floor and the dirt extracted from the floor covering by the suction created at the nozzle by the fan, is discharged through the

exhaust passage and into the bag 6. The fabric of the bag is permeable in a degree to the air entering the same under pressure, so that while it is inflated during the operation of the cleaner, sufficient air escapes through the fabric to avoid the creation of any considerable back pressure, a condition that exists so long as the bag remains relatively clean. However, after the cleaner has been in operation for a considerable period of time, the dirt accumulating in the bag reduces the permeability of the fabric, and causing a back pressure that is evidenced by a material decrease in the efficiency of the cleaner.

Thus as a means of indicating the condition within the bag and particularly, to warn the operator that the bag is dirty and requires cleaning, the indicator 10 is located adjacent the upper end of the bag as clearly shown in Figure 1. By preference an opening is provided at the point where the indicator is located, this opening being formed in the fabric of the bag and reinforced by a metal ring 11, although a rubber plug 12 may be fitted into the opening, as shown in Figure 2, in the event the indicator is to be omitted or until such time as one is to be installed.

Referring now to Figures 3, 4 and 5, the indicating device 10 comprises parts as follows: An annular plate 13 having a slightly rounded or convex exterior surface forms a body member or support for the moving parts of the indicator including a bellows type of pressure responsive element 14 consisting of a cup-shaped member of flexible material with corrugated annular side walls and a flat bottom wall. This bellows member is secured centrally of the body member by means of an L-shaped collar 15 having a radial flange seating in a recess 13a in the inner face of the body member and clamping therebetween the outwardly turned margins of the bellows. The collar 15 is suitably fastened or anchored to the body member 13 with its radially flanged portion substantially flush with the inside face thereof, said collar having an angular flange projecting beyond said inside face for insertion through the ring 11 reinforcing the opening in the fabric of the bag. The flanged portion of the collar 15, projecting through the opening in the bag, is threaded to receive a lock ring 16 which is screwed thereon from the inside of the bag to hold the indicator securely in place.

At the center of the outer face of the plate 13 is a slightly rounded circular projection bisected by a vertical slot 17 and adapted to move lengthwise of this slot is an arm 18 journaled on

a pin 19 extending transversely between two ears 20, 20 formed integrally with the plate 13 and projecting at right angles from its inner face on both sides of the slot 17. At its pivoted end, the 5 arm 18 has a short lever arm 18a arranged at right angles thereto, with its end connected at the center of the end wall of the bellows 14 by means of a short link 21 and a pin 22 anchored in said end wall, the latter, as clearly shown in Figure 4, being preferably reenforced on opposite 10 sides by circular reenforcing plates 14a—14a. And finally, a light spring 23 is coiled around the pivot pin 19 of the arm 18 with a U-shaped portion 23a straddling the arm 18, as is clearly 15 shown in Figures 4 and 5, and its ends abutting a cross pin 24 extending between the ears 20, thus normally holding the arm at the lower end of the slot 17. The tip end of the signal arm 18 is preferably colored in red or some other readily visible 20 color, so that its position in the slot 17 can be easily seen by the operator.

Under normal operating conditions, that is to say, when the bag is clean, the indicator arm 18 is held at the lower end of the slot, which position is designated by the word "Clean". As long as the pressure within the bag does not exceed a predetermined maximum the signal will not change position, but when the pressure, due to the excessive accumulation of dirt in the bag, 30 becomes great enough to overcome the combined resiliency of the bellows 16 and the tension of the spring 23, the bellows will contract thus actuating the indicator arm 18 causing the signal to move toward the opposite end of the slot 17 designated by the word "Dirty". Manifestly, the movement of the signal is an indication of excessive dirt in the bag and registers its warning when the cleaner is in operation and until the bag has been emptied, whereupon the signal arm 40 will return to the "clean" position and so remain until the bag again requires cleaning.

Figures 6, 7 and 8 show a modified construction for a bag pressure indicator somewhat similar to that just described, but embodying a different 45 form of signal. The body of the indicator comprises a two-part casing, made up of a circular plate-like member 25 and a tubular member 26, having an annular flange portion 26a concentric with said plate member. As clearly shown in Figure 7, the inner contacting marginal faces of the two sections 25 and 26 are provided with interfitting annular shoulders and recesses between which is clamped the fabric around an opening formed in the bag and the whole fastened together by rivets 27. The tubular member 26 of the casing is located on the inside of the bag and is preferably disposed at an angle of substantially 30 degrees to the plane of parting of the two body forming members. Extending axially 50 of the angularly arranged tubular portion is an integral bearing 28 having an axial bore supporting a rod 29 constituting the signal member. Closing the inner end of the tubular member 26 is a bellows member 30, identical in every respect 55 to the bellows member 14 shown in Figure 4. This bellows member is suitably fastened over the end of the tubular portion, thus forming a cavity or chamber sealed from the interior of the bag 6. The rod or signal member 29 is attached at its 60 inner or lower end to the center of the end wall of the bellows member 30 and surrounding the rod between said end wall and the adjacent end of the bearing 28 is a coil spring 31 acting to hold the bellows member in extended position and to 65 oppose its contraction under the pressure of 70

the air in the bag and the accompanying endwise movement of the signal member 29. The outer free end of the signal member or rod 29 is supported by a separate bearing 25a integral with the member 25 and projecting obliquely from its inner face in alignment with the main bearing 28 supporting the signal rod 29.

And finally, as shown in Figure 7, the outer end portion 29a of the rod is tipped in some readily distinguishable color such as red, but 10 under normal conditions of operation the rod is retracted into the outer bearing 25a to such an extent that the tip end thereof is not visible to the operator.

However, when the bag becomes dirty and the 15 pressure increases therein, it follows that the bellows member 30 will be contracted, thus shifting the signal rod endwise and in an upward direction, whereupon the tip thereof appears in the somewhat enlarged entrance to the bearing 25a as a red spot between the arrows marked on the outer face of the plate, as clearly shown in Figure 6, the appearance of this red spot manifestly indicating that the bag should be emptied.

In construction, function and purpose both 25 types of pressure indicators are quite similar, being sufficiently light and compact to be readily incorporated in the bag and supported by the fabric. This permits the positioning of the indicator considerably nearer the operator than is 30 otherwise possible and at a point where the signal is more likely to be observed. Therefore, except for the fact that one type of indicator is arranged to register the existing condition in the bag as "clean" or "dirty" and the other type to 35 display a visual warning signal when the bag is to be emptied, both are equally satisfactory and useful adjuncts to a suction cleaner.

Having set forth a preferred embodiment of my 40 invention, I claim:

1. In a pressure indicator for the purpose described, the combination with a container of flexible material having an opening formed in the wall thereof, of a relatively flat body member fastened to the exterior surface of said container 45 with its central portion registering with the opening therein, a bellows member fastened to said body member and subject to the pressure changes in said container, and a signal member operatively connected with said bellows member and 50 having its end portion tipped with a contrasting color, said body member having a slot there-through in which the end of said signal member is visible to indicate pressure changes in said container.

2. In an air pressure indicator for the purpose described, the combination with a container of flexible material having an aperture formed at a predetermined point in the wall thereof, of a relatively flat body member inserted into said 60 aperture in the wall of said container and clamped about the margin thereof, said body member having a cavity in the rear face and a slot extending through to the front face thereof, a pressure responsive element mounted on the 65 rear face of said body member and enclosing said cavity, and a signal member carried by said member and operatively connected with said pressure responsive element and having a visible portion shiftable in said slot to indicate pressure 70 changes within said container.

3. In a pressure indicator for the purpose described, the combination with a container having a wall of flexible material and an aperture formed in said wall, of a relatively flat annular 75

body member adapted to be clamped about its margin to the material of said container about said aperture, and having a recessed central portion provided with a slot visible on the outer face thereof, a bellows member closing off said recessed portion and exposed to the pressure with-

in said container, and a signal member on said body member and operatively connected with said bellows member and comprising an arm adapted to swing lengthwise in said slot to visually indicate variations in air pressure in said container. 5

DALE C. GERBER.
